Fred Marin

ATTORNEY.

UNITED STATES PATENT OFFICE

ROBERT H. NICHOLSON, OF LOS ANGELES, CALIFORNIA

MARKING PLATE FOR KEYS AND METHOD OF SECURING SAME

Application filed January 25, 1932. Serial No. 588,689.

My invention relates to keys and is illustrated as applied to a flat metal key adapted for use in pin tumbler locks. My invention is particularly adapted for use in keys used in connection with safety deposit boxes of bank vaults and this use will hereinafter be described to illustrate one use of my invention.

Safety deposit boxes are commonly metal boxes, each provided with an individual lock and one or more individual keys, the boxes being arranged inside a bank vault. These boxes are rented to the general public and are usually serially numbered, each of the keys bearing the number of the box to which it applies. Whenever the user of a box ceases to use same and surrenders his keys it is necessary to change the lock and key on that box to prevent the former user from obtaining access to the interior of the box by means of a duplicate key which he may have had made while the keys were in his possession.

The usual practice is to remove the lock from the box with which it has been used and interchange it with a lock from another box.

It is necessary to mark the key with the number of the box to which it applies. When the lock is changed to another box the number then on the keys corresponding to the lock does not correctly indicate the new box to which the lock has been applied and the number on the keys must be removed and the number of the new box placed thereon.

It is an object of my invention to provide means by which the number on the keys can be readily and cheaply changed.

Further objects and advantages will be made evident hereinafter.

In the drawing:

Fig. 1 is a perspective view of a key with a tightening tool in place therein.

Fig. 2 is a side elevation partly in section showing the method of using the tightening tool, and

Fig. 3 is a view of a portion of a key adapted to be used in practising my invention.

Fig. 4 is a view of a number plate adapted to be used in the key shown in Fig. 3.

Safe deposit boxes are ordinarily provided

with pin tumbler locks, often called Yale locks, which are adapted to be opened with a flat metal key. My invention is well adapted to be applied to such keys which are provided with heads 11 as shown in Fig. 3. These heads may be circular, as shown, or of some other form. Each of these heads is provided with a cylindrical opening hole 12 for attachment to a key ring, not shown.

Stamped in the head adjacent the opening 12 is a number plate perforation 13 in which a number plate 14 fits. By stamping out all the perforations 13 with the same die it is possible to make them all of about the same size and the metal removed from the head in forming the perforation 13 can be used as the initial number plate 14. The perforation 13 and the number plate 14 are thus the same size and shape, and if the number plate 14 is forced back into the perforation 13 it will usually be frictionally gripped with sufficient force to hold it in place. Whenever it is desired to interchange locks on two boxes the number plates of the respective keys can be forced out of the keys and interchanged.

Small variations in the size of the perforations 13 and the plates 14 affect the tightness with which the number plates 14 are held in the perforations 13. If any plate 14 is slightly oversize the plate 14 may be reduced in size or the perforations 13 can be increased by filing. If, however, any plate 14 is too small or any perforation is too large it is not practical to add metal thereto.

I have found, however, that by making the wall 15 of the perforation 13 adjacent the opening 12 roughly concentric with the opening 12 I form what I term a spring bridge 16 of the material between the opening 12 and the perforation 13. This spring bridge 16 has considerable resiliency and may be distorted slightly to allow a number plate 14 to be sprung in place and exerts a spring pressure on the plate when it is in place.

If for any reason the number plate is slightly too small, the perforation 13 can be reduced in area by placing a conical spreading tool 20 in the opening 12 and striking it sharply with a hammer 21. This enlarges the opening 12, spreading the walls thereof,

and crowding the metal of the spring bridge 16 over so that its pressure on the number plate 14 is increased. It is thus possible to lock a number plate 14 in a perforation 13 5 even though the number plate 14 is slightly smaller than the perforation 13.

It should be understood that the changing of locks on safe deposit boxes is usually performed on the premises where the boxes are 10 situated by a workman specialized in this service. It is therefore necessary that any tools used shall be simple and readily portable, which are advantages possessed by my invention.

15 I claim as my invention:

1. A key formed of sheet metal and adapted to be used in pin tumbler locks, comprising: a ward portion; a head, said head having a perforation extending entirely there- 20 through, and a cylindrical opening adapted to receive a key ring; and a marking plate (of substantially the same thickness as said head) fitting in said perforation, said perforation being so formed that the side thereof 25 adjacent said opening is concentric with said opening, thus leaving a spring bridge between said perforation and said opening, said bridge being adapted to engage each marking plate with a yieldable pressure to retain same 30 in place.

2. A method of securing a marking plate in a key head, which comprises: forming a perforation extending entirely through said head and adapted to receive a marking plate of the same thickness as said head; forming a 35 circular ring-opening entirely through said head adjacent said perforation in such a position as to leave a spring bridge between said opening and said perforation; inserting a marking plate in said perforation; and expanding said spring bridge against said marking plate by pressure applied to the wall of said opening.

3. A key of the character described, having: a head provided with a pair of perforations formed therethrough which are separated by a deformable bridge; and a marking plate fitted in one of said openings and being engaged by said deformable bridge which 50 retains same in place.

In testimony whereof, I have hereunto set my hand at Los Angeles, California, this 20th day of January, 1932.

ROBERT H. NICHOLSON.

CERTIFICATE OF CORRECTION.

Patent No. 1,892,995.

January 3, 1933.

ROBERT H. NICHOLSON.

It is hereby certified that error appears in the printed specification of the above numbered patent requiring correction as follows: Page 2, line 28, claim 1, for "each" read "said"; and that the said Letters Patent should be read with this correction therein that the same may conform to the record of the case in the Patent Office.

Signed and sealed this 28th day of February, A. D. 1933.

(Seal)

M. J. Moore,
Acting Commissioner of Patents.
